WIRE BOUND BOX LIDDING MACHINE

John R. Richards, Riverside, Calif., assignor to Food Machinery and Chemical Corporation, San Jose, Calif., a corporation of Delaware

Application December 26, 1951, Serial No. 263,307

17 Claims. (Cl. 100—56)

This invention relates to box lidding machines and pertains more particularly to an improved mechanism for closing and fastening the lids of wire bound boxes.

Such boxes are constructed principally of thin flexible boards, and have their lids hingedly attached thereto by encircling wires which terminate in loops, one of which projects from a forward edge of the lid, and the other from an upper edge of the front side of the box. When such boxes are used for the packing and shipping of fruit and produce, they usually are overfilled, so that in closing the lid of the box, the thin flexible boards of which they are constructed are arched or crowned, so that this type of packing has become known in the industry as "crown packing".

An object of the present invention is to provide an improved box lidding mechanism for use in the crown packing of wire bound boxes.

Another object is to provide improved means for straightening, aligning and interengaging, and then bending to interlocked position, the terminal wire loops on the front side and lid, respectively, of a wire bound box.

A further object is to provide improved lid positioning and securing means for a wire bound box lidding machine.

Another object is to provide improved lid aligning means for a wire bound box lidder, which means also retain the produce within the confines of the box during a lid closing operation.

These and other objects and advantages of the invention will be apparent from the following description and the accompanying drawings wherein:

Fig. 1 is a side elevational view of a machine embodying the present invention, portions thereof being broken away.

Fig. 2 is a front elevational view of the upper portion of the machine shown in Fig. 1.

Figs. 3 and 4 are fragmentary side elevational views showing selected portions of Fig. 1 in different stages of their operation from that shown in Fig. 1.

Figs. 5, 6 and 7 are diagrammatic views in the nature of enlarged fragmentary side elevations showing successive stages in the operative cycle of a lid positioning portion of the present invention.

Figs. 8, 9 and 10 are enlarged diagrammatic views in the nature of enlarged fragmentary side elevations showing a wire loop straightening portion of the invention in successive stages of its operation, Fig. 10 showing additionally, in broken lines, the roller hammer in its final position after interlocking the interengaged wire loops.

Fig. 11 is a diagrammatic view in the nature of a fragmentary section taken along line 11—11 of Fig. 9.

Fig. 12 is a further enlarged perspective view showing a wire loop straightening assembly as it would appear when removed from the machine, a portion of the supporting shafts therefore also being shown.

In general, the principal structural and operative parts of the illustrated lidding machine are similar to those

2

shown in the co-pending application of Ernest A. Verrinder, Serial No. 246,134, for Lidder for Wire Bound Boxes, filed Sept. 11, 1951. Briefly, these principal parts comprise a stationary frame 20 having a top frame structure 21 rigidly mounted thereon, a box elevating hoist 22, and a pair of downwardly spring biased, lid closer support members 23 mounted for vertical sliding movement on the frame 20.

A lid closing frame 24 is mounted for limited tilting movement between a pair of slotted plates 25, carried by the vertically movable lid closer support members 23. A pair of side frame members 26 of the lid closing frame 24 extend forwardly therefrom, and are notched at 27 on their under sides for a purpose which will be explained later herein. The hoist 22 has a top frame portion 22a thereon, and two box end presser members 28 are pivotally mounted on the top frame portion to be swung inwardly by a pair of cams 29 into pressing engagement with the ends of a box 30 upon elevation of the box by the hoist. The cams 29 for actuating the box end presser members 28 are welded one to the forward edge of each of the slotted plates 25.

As in the machine of co-pending application, Serial No. 246,134, referred to previously herein, the lid closer support members 23 are mounted to slide on gib posts 31, a pair thereof being provided for each support member. The support members 23 are maintained horizontal during their vertical movements along the gib posts by pinions 32 meshed with racks 33. The pinions 32 are arranged in pairs, each pair thereof is secured to opposite ends of a shaft 34 journaled in a pair of brackets 35 provided therefor on each lid closer support member 23. The racks 33 are secured to the top frame structure 21.

Diagonally disposed coil springs 36 are mounted under compression between the fixed top frame structure 21 and the slidable lid closer support members 23 to bias the lid closer support members downward during a lid closing portion of the stroke of the hoist 22, but to allow said slidable members 23 to travel upwardly against the biasing force of the springs 36 during a subsequent loop-interlocking portion of the hoist stroke.

The hoist 22 may be of a well known hydraulic type with suitable controls (not shown), such as conventional manually operated valve means, or by automatic controls, such as those illustrated and described in the co-pending application Ser. No. 246,134 referred to previously herein. The hoist 22 is adapted to be elevated to a desired height upon actuation of the control means so as to perform the lid closing and loop straightening, aligning and interlocking operations in a manner to be described herein, and then to be lowered again to its starting position shown in Fig. 1 after the lidding has been completed.

Box supporting anvils 38 are mounted on the hoist top frame 22a to support, at its ends, the box 30 to be lidded. Guide flanges 39 are mounted along the outer sides of the anvils 38 to guide the box to a centered position thereon.

A box front supporting member is provided to support the front wall of the box against bulging during compression of its contents. This support member comprises a box front presser assembly 40 adapted to be swung into pressing engagement with the front wall of a box during an operative stroke of the hoist 22. One of a pair of standards 41 is secured to extend upwardly from each side of the hoist top frame 22a laterally beyond the anvils 38. A pair of presser assembly support arms 42 is pivotally mounted, one on the upper end of each of the standards 41, and the box front presser assembly 40 is mounted on the free ends of the arms 42.

Downward swinging of the front presser assembly sup-

port arms 42 during an upward stroke of the hoist 22 is accomplished by a pair of cam follower rollers 44 mounted, one on each of the presser assembly support arms 42. Each of the cam follower rollers 44 is adapted to ride into a laterally extending notch 45 (Figs. 1, 3 and 4) in a notched cam plate 48 when the hoist 22 approaches its lowered position as shown in Fig. 1 to swing the arms 42 and the front presser assembly 49 upwardly. The notched cam plates 48 are secured to the slidable lid closer support members 23 to extend downwardly therefrom.

Upon elevation of the hoist 22, the rollers 44 are retained against upward movement by the upper edges of the notches 45 of the associated cam plate 48 until the presser assembly 49 is pressed into engagement with the front face of a box 30 to be lidded. At this point, the rollers 44 roll rearwardly out of their notches 45 and upwardly along the rear faces 49 of the cam plates 48 as shown in Figs. 3 and 4.

The front presser assembly 49 comprises a presser plate portion 50 having a box-like lower portion 51 (Figs. 1 and 2) of rectangular cross-sectional shape. A plurality of fingers 52 extend upwardly from the lower portion 51 to lie closely against the front of the box and substantially midway between adjacent binding wires 30a thereof when the presser assembly 49 is in its lowered position (Figs. 2, 3 and 4). These fingers are of a length to extend above the top of a box to be lidded to prevent the overfilled contents of the box from extending forwardly when the lid is closed. Tapered angular reinforcing ribs 53 (Figs. 2 and 3) are welded to extend forwardly from the outer face of each finger 52, the lower end of the ribs being welded to the upper side of the box-like lower portion 51.

End plates 54 are welded to the ends of the presser plate portion 50 and are secured by bolts 55 to the free ends of the presser plate support arms 42. The end plates 54 are of generally trapezoidal shape (Figs. 1, 3 and 4) and a loop straightener support shaft 57 is journaled therein to lie forwardly of the terminal loops 30b of the binding wires 30a on the front wall of a box 30 when the arms 42 have been swung down to bring the presser plates 50 against the front wall of the box 30 as described previously therein.

A plurality of loop straightening and aligning assemblies 60 are mounted on the shaft 57, and since these assemblies are all substantially alike, only the one on the left hand end of the shaft 57 will be described in detail. For the purpose of the present portion of the description, the assembly 60 will be assumed to be in its up-swung or loop straightening position as shown in Figs. 9 and 11.

The loop straightening and aligning assembly 60 (Figs. 9 to 12, inclusive) comprises a hub portion 61 secured by set screws 62 to the shaft 57. A pair of parallel support arms 63 are secured to extend radially from the hub 61. A head portion 60a is pivotally mounted on the free ends of the arms 63 and comprises a central plate portion 64 having a block 65 welded thereto and drilled to receive a pivot pin 67 which also is inserted in holes provided therefor in the arms 63. The upper and lower marginal portions 68 and 69 of the plate portion 64 are bent toward the arms 63, so as not to leave exposed edges which might catch on portions of the box or its binding wires during a lid closing operation.

Oppositely symmetrical side wing portions 70 and 71 are welded one to each side of the central plate portion 64 to extend laterally therefrom. These wing portions are of a length to extend upwardly beyond the central plate portion 64. The upper and lower marginal portions 72 and 73 of each wing portion are bent to correspond with those of the central plate portion 64. The upper inner corners 74 (Figs. 11 and 12) of the side wing portions 70 and 71 are clipped diagonally to provide upwardly diverging guide edges for guiding a lid loop 30c of a binding wire 30a to centered position therebetween during the closing of the box lid.

When the straightener assemblies 60 are in engagement with a box 30, in the position illustrated in Figs. 2, 9, 11 and 12, the upstanding wing portions 70 and 71 of each assembly 60 extend above the upper edge of the front wall 5 of the box 30. Hence, the wings 70 and 71 constitute auxiliary box front support members cooperating with the upper portions of the fingers 52 (Fig. 2) to form a retainer wall which prevents produce from flowing over the front wall as the lid moves toward closing position. 10 Since the pivoting, closing action of the lid tends to move the produce toward the front of the box, it is important that a wall be provided for supporting the produce during the final closing movements of the lid. In Fig. 9, the produce support members 70 and 71 are shown in the 15 position in which the forward edge of the box lid passes close to the support members 52, 70 and 71 to contact the produce disposed thereagainst and force it downwardly into the box.

The outer wing portion 71 (Figs. 11 and 12) of the 20 loop straightening assembly 60 on each end of the shaft 57 is cut as at 75, and the tab portion 76 formed thereby is bent toward the arms 63 for receiving the impact of the notched, forwardly projecting portions 27 of the side bars 26 of the lid closing frame 24 during the final portion 25 of its lid closing movement. This impact of the lid closing frame overcomes any frictional engagement between the loop straightening assemblies and the box, and assists gravity in swinging the loop straightening assemblies 60 downwardly clear of the box upon completion of a loop 30 straightening and aligning operation thereby.

A pointed loop straightening prong 77 is mounted 35 centrally of the central plate portion 64 with its pointed end directed upwardly so as to enter and to straighten, by pulling it upwardly, a loop on the front side of the box. 40 Each prong 77 has a thickened base or mounting portion 78 terminating at its upper end in a shoulder 78' from which a thinner pointed portion 79 (Fig. 12) extends upwardly; and the base portion is affixed to the central plate portion 64 midway between the side wings 70 and 71. 45 The base portion is sufficiently thick to provide clearance between the pointed portion 79 and the central plate portion 64 slightly greater than the diameter of the binding wire 30a for the boxes to be lidded. This avoids the possibility of the wire becoming jammed between the prong portion 79 and central plate portion 64.

A coil spring 83 is mounted in tension between the 50 lower edge of the central plate portion 64 and an arm 85 secured to the hub 61 to urge the head portion 60a about the pin 67 as a pivot.

A stop screw 80, for limiting the pivotal movement of the head portion 60a under the tension of the spring 83, is screwed into a post 81 secured to extend at right angles from a side of the arms 63. The stop screw 80 55 is locked in adjusted position by a lock nut 82 to engage the central plate portion 64 and to arrest pivotal movement of the head portion 60a in a position substantially at right angles to the arms 63.

The operating mechanism 87 (Figs. 1 to 4 and 8 to 10, 60 inclusive) for the loop straightening and aligning assemblies 60 comprises a cam actuated series of links and levers. A shaft actuating lever arm 88 is secured to an end of the shaft 57 upon which the loop straightening and aligning assemblies 60 are mounted. The free end 65 of the arm 88 is connected by a link 89 to the free end of a lever arm 90 pivoted on a stud 91 on one of the presser plate support arms 42. The lever arm 90 has a recess 92 in its pivotally mounted end, and a lever 93 is fitted into this recess so as to be free for pivotal movement through an angle of approximately 180° relative to the recessed arm 90, but to engage the offset shoulder 94 between the recess 92 and the remainder of the arm 90 at each end of such swinging movement. Any further 70 movement of the lever 93 in engagement with the offset 75

shoulder 94 causes the recessed arm 90 to move therewith in the nature of a bell crank lever.

A light coil spring 95 is mounted in tension between the relatively pivoted lever 93 and a bracket 97 welded to the recessed lever arm 90. The spring 95 urges the arm 93 into arrested position against one end of the shoulder 94. Thus, as shown in Figs. 1 and 10, the relatively pivoted spring biased lever 93 is free to swing clockwise against the tension of the light coil spring 95 through an angle of approximately 180°, for example, without applying any substantial torque to the recessed lever arm 90. When rotated in a counterclockwise direction, i. e., as from the position shown in Fig. 8 to that shown in Fig. 9, the lever 93, by its abutting engagement with the shoulder 94 of the lever arm 90, will swing the recessed lever arm 90 therewith, and, through the link 89 and lever arm 88, will swing the loop straightening assemblies 60 clockwise, moving the head portion 60a rearwardly and upwardly to the position shown in Fig. 9.

For controlling the operation of the relatively pivoted lever 93, and thereby of the loop straightening assemblies 60, a cam follower roller 98 is mounted rotatably on the free end of the spring biased lever 93. The roller 98 is positioned to engage a forwardly sloping cam surface 99 at the lower end of the forward edge of its associated notched cam plate 48 at a stage in the upward operative stroke of the hoist 22 after the front presser assembly 40 has been swung downwardly against the front wall of the box 39. This forces the roller 98 forwardly, as will be apparent from Fig. 9, and, through the operating mechanism described previously herein, will swing the loop straightening assemblies 60 clockwise to their up-swing position as shown in Figs. 2, 3, 9 and 11. The loop straightening assemblies 60 are retained in their up-swing position until the roller 98 reaches the upper end of a straight vertical forward edge portion 99a at which stage of operation (Fig. 9) the notched, forwardly projecting end portions of the side bars 26 of the lid closing frame 24 are about to engage the bent tab portions 76 (Fig. 12) of the end loop straightening and aligning assemblies 60.

At this point in the elevating stroke of the hoist 22, the roller 98 on the arm 93 rides off the edge portion 99a and into a rearwardly offset portion 100 in the forward edge of the notched cam plate 48. This frees the spring biased, relatively pivoted lever 93 and the recessed lever arm 90 for clockwise relative movement, and by means of the link 89 and lever arm 88, frees the shaft 57 for counterclockwise rotative movement. The loop straightening and aligning devices 60 thereupon drop by gravity to their depending position shown in Fig. 10, assisted by the impact of the notched lid frame side members 26 on the tabs 76 of the outermost assemblies 60.

The lid closing frame 24, which is mounted to ride freely between the slotted plates 25 has the side bars 26 thereof (Figs. 1, 2, 3, 4 and 9) connected at their rear ends to a bar (not shown), and at their front ends to a plate 102 welded to extend therebetween. A forwardly sloping cam plate 103 for swinging a plurality of loop interlocking roller hammers 104 into loop engaging position, as the hoist 22 continues its upward movement after the closing of a box lid, is mounted to extend lengthwise over the front frame plate 102. The forward edge of the cam plate 103 is positioned to align with the front of a box upon completion of the lid closing operation. The rear edge 105 of the sloping cam plate 103 is supported by a buttress strip 108 mounted between the cam plate 103 and the front plate 102 of the lid closing frame 24.

The rear end of the lid closing frame 24 has a pair of studs 110, only one of which is shown, mounted on opposite sides thereof to extend through slotted openings 111 in the slotted plates 25 and to project laterally beyond the plates 25. A guide roller 112 is mounted rotatably on each stud 110 to ride in the slot 111 through 75

which the stud projects. A stop lug 113 is mounted on the inner side of each slotted plate 25 to extend over the lid closing frame 24 and is positioned at a height on the slotted plates to arrest the upward travel of the rear portion of the cover closing frame 24 at the stage of hoist operation at which the box lid 30d is fully closed.

The forward portion of the lid closing frame 24 is connected by adjustable links 114 (Figs. 1 to 4) to the slideable, spring biased, lid closer support members 23. The lower end of each link 114 is pivoted on a stud 115 on each side member 26 of the lid closing frame 24, while the upper ends of the links 114 are pivoted on studs 116 on the slideable spring biased members 23.

One of the loop bending rollers hammers 104 is provided in vertical fore-and-aft alignment with each pair of interengaging wire loops 30b and 30c on a box to be lidded. Each roller hammer 104 comprises a pair of side bars 117 and 118 pivoted at their upper ends on a shaft 119 mounted in openings 120 provided therefor in a pair of bars 121 clamped by bolts 122 to the rigid top frame 21. A web 123 (Fig. 2) is secured between the side bars 117 and 118 of each hammer 104, to extend transversely thereacross. A cam contacting roller 124 is journaled on a pin 125 mounted transversely of the lower ends of the hammer side bars 117 and 118 to engage the sloping cam plate 103 on the lid closing frame 24 during an operative stroke of the hoist 22.

For arresting the forward swinging movement of the hammers 104 as they roll off the forward edge of the cam plate 103, and to force the rollers 124 into pressing, rolling engagement with the box front during a final portion of each elevation of the hoist 22, a hammer stop support plate 127 (Figs. 1 and 2) is mounted on the hammer support shaft 119 and on a second shaft 128 spaced forwardly therefrom. The second shaft 128 is mounted in holes provided therefor in the same bars 121 which support the hammer pivot shaft 119.

For resiliently urging the roller hammers 104 to swing rearwardly to the position shown in Fig. 1, a guide lug 130 is welded to the side of each stop support plate 127 forwardly of each hammer 104. A pin 131 is pivotally connected to each hammer 104 and is slidably inserted in a hole provided therefor in its associated guide lug 130. A coil spring 132 surrounds the pin 131 and is held in compression between the lug 130 and the hammer 104, normally to urge the hammer 104 to its rearwardly swung position shown in Fig. 1. A stop nut 133 is provided on the threaded forward end of the pin 131 to limit rearward swinging movement of the hammer to a position where the roller 124 on the lower end of the hammer 104 will contact the sloping cam plate 103 on the lid closing frame 24 when the latter is elevated to the position shown in Fig. 4 during a lidding operation.

For limiting the forward swinging movement of the hammers during a lidding operation of the machine, a stop screw 134 is screwed to adjusted position into a threaded hole provided therefor in a second and lower lug 135 secured to extend from each stop support plate 127 below the lug 130 thereon. A lock nut 137 locks each stop screw 134 in adjusted position. The stop screws 134 are positioned to engage the transversely extending strip portions 123 of their associated hammers 104 to limit the forward swinging movement of the latter by the cam plate 103 on the lid closing frame 24. Thus, the hammer rollers 124 will roll, upon engagement of the hammers 104 with the stop screws 134, down the front of the box to bend into interlocking engagement and roll over each pair of interengaged wire loops 30b and 30c of the box encircling wires 30.

Mechanism is provided for pressing against the rear side of the box 30 to oppose the rearward thrust of the presser assembly 40 and of the hammer rollers 124 to assist generally in maintaining the overfilled box in rectangular form. This mechanism is constructed so that

it also tucks into proper position any rearwardly displaced lids on the boxes 30 being lidded.

This lid tucking and rear presser mechanism 140 (Figs. 1 to 4 and 5 to 7, inclusive) comprises an angle bar 141 having a rounded nose portion 142 secured to a shaft 143 extending transversely between a pair of slidably mounted tucker support plates 144. The tucker support plates 144 are mounted for vertical sliding movement, one on each of the vertically slotted plates 25. Each of the tucker support plates 144 is slotted at 145 to receive the projecting end of the stud 110 on the lid presser frame for limited relative vertical movement therein.

Each slidably mounted tucker support plate 144 is guided for vertical movement by the rollers 112 on the lid closer frame studs 110 riding in the slotted opening 111 in the slotted plates 25. A second roller 147, mounted on a stud 148, mounted on the upper end of each slidably mounted plate 144 to extend inwardly therefrom, also rides in the slotted opening 111 of its adjacent plate 25 to retain the sliding plate 144 against pivotal displacement about the associated studs 110.

A triangular tucker actuating member 150 is pivoted at one corner thereof on the upper roller support stud 148 exteriorly of each tucker support plate 144, and a second corner of the triangular member 150 is connected by a link 151 to an arm 152 secured to the shaft 143 of the tucker member 141. A cam follower roller 153 is mounted for free rotation on a stud 154 which projects inwardly from the third corner of the triangular tucker actuating member 150.

The roller 153 is positioned to engage the lower end of a cam bar 155 secured to the outer face of the slotted plate 25 alongside the slotted opening 111 therein when the slidably mounted plates 144 are moved upwardly from their lowermost position shown in Fig. 1 by an elevating stroke of the hoist 22. The upward movement of the slidably mounted plates 144, from their position shown in Fig. 1 to that shown in Fig. 3, causes the roller 153 to engage the lower end of the cam bar 155, and thus to swing the triangular plate 150 upon which the roller 153 is mounted clockwise about its mounting stud 148.

This movement of the triangular plate 150, by means of the link 151 and arm 152, swings the angle bar 141 in a counterclockwise direction from its outwardly swung position shown in Figs. 1 and 5, to the position shown in Figs. 4 and 7. This action of the angle bar 141 tucks any rearwardly displaced lids forwardly into proper position for closing as shown diagrammatically in the sequence of operative positions illustrated in Figs. 5 to 7, inclusive. During the remainder of the upward stroke of the hoist 22, the cam follower roller 153 rides upwardly along the rear edge of the cam bar 155 as shown in Fig. 4, and thus retains the angle member 141 in its forwardly swung position to support the upper portion of the rear side of the box against bulging and rearward displacement.

The angle member 141 is returned to its normal position shown in Fig. 1 at the end of each downward or return stroke of the hoist 22. This return swing of the angle member 141 is caused by a second cam plate 157 having a forwardly sloping cam face 158 thereon. The second cam plate 157 is positioned to be engaged by the roller 153 and to deflect it forwardly upon its return to its lowermost position shown in Fig. 1. This forward deflection of the roller 153 swings the triangular plate 150, and, by means of the link 151, the lever arm 152 and angle member 141 back to their normal positions of Fig. 1.

The slidably mounted tucker support plates 144 are actuated vertically in timed relation with the rest of the machine by means of raising or lowering of the hoist 22 through stops 159 and 160 (Figs. 1 to 4) secured in adjusted positions on a pair of thrust rods 161, 161.

The upper end of each thrust rod 161 is secured to one of the slidably mounted tucker support plates 144. The stops 159 and 160 are positioned to be engaged by the hoist top frame 22 at predetermined stages in the actuation of hoist 22. The upper stops 159 for raising the tucker support plates 144, and thereby the rear end of the lid closing frame 24, are positioned on their respective thrust rods 161, 161 at a height which will move the rear end of the lid closing frame 24 upwardly against the stop lugs 113 on the inner sides of the slotted plates 25 at the stage in the elevation of the hoist 22 where the under side of the lid closing frame 24 is parallel to the anvils 38, 38 and at box height therefrom. The lower stops 160 are positioned on their respective rods at a height which will restore the parts to their lowered positions shown in Fig. 1 when the hoist 22 returns to its fully lowered position.

The slotted holes 145 in the slidably mounted plates 144 in which the studs 110 on the rear end of the lid closing frame 24 are mounted, permit limited relative vertical movement between the slidably mounted tucker support plates 144 and the studs 110 on the rear of the lid closing frame. This freedom for limited relative movement allows the rear tucker member 141 to be swung forwardly against the box 30 by the initial upward movement of the slidably mounted plates 144. This movement preferably occurs before the marginal portions at the lower ends of the slotted holes 111 engage the studs 110 to initiate their upward movement and that of the rear end of the lid closing frame 24 upon which these studs are mounted.

The operation of the lidding machine itself is similar to that described in co-pending application, Serial No. 246,134, referred to previously herein, and will not, therefore, be repeated in detail. Briefly, however, upon elevation of the hoist 22, with a box 30 centered on the anvils 38, the end presser bars 28 are forced inwardly by the cam bars 29 to support the ends of the box against bulging. The lid 30d of the box 30 then is engaged by the lid closing frame 24 and is swung to closed position as shown in Fig. 4. Thereafter, continued elevation of the hoist forces the sloping cam plate 103 against the rollers 124 on the roller hammers 104, camming them forwardly until they are arrested by the stop screws 134. The roller 124 on the roller hammers 104 then roll relatively downwardly along the front of the box, bending the interengaged loops 30b and 30c into interlocked position to complete the lidding operation. The hoist 22 then is lowered, restoring the parts to the positions shown in Fig. 1.

During the elevation of the hoist 22, the arms 42 are swung downwardly by the action of the hook-shaped cams 48 on the cam follower rollers 44 to bring the front presser assembly 40 into pressing contact with the front 55 of the box 30, and with the fingers 52 thereon located between adjacent loops 30b on the front side of the box.

As the roller 98 on the pivotally mounted arm 93 of the loop straightening mechanism rolls upwardly along the sloping lower front edge portion 99 of the hook-shaped cam 48 (Fig. 8), the loop straightening assemblies 60 are swung from their dependent position as shown in Fig. 10, to their upswung, loop straightening position shown in Fig. 3. As the loop straightening assemblies 60 thus are swung upwardly and rearwardly in a clockwise direction, the 65 pointed upper ends of the prongs 77 enter the loops 30b on the front of the box and draw them upwardly, tautening the wires thereof and bringing them to an upstanding position best suited to enter the lid loop 30c when the lid 30d is swung to its closed position shown in Figs. 4, 10 and 11. Also, as the lid approaches its closed position, in the event that the forwardly extending lid loop 30d is displaced laterally from a proper, forwardly extending position, the diverging edges 74 of the side wings 70 and 71 will tend to center the lid loop therebetween. As the lid is swung to the almost closed position shown in Fig. 9,

the roller 98 runs off the upper end of the vertical front edge 99a of the hook-shaped cam 48, freeing the lid straightening assembly 60 for counterclockwise rotative movement from its position of Fig. 9 to that of Fig. 10. At this stage in the elevation of the hoist 22, the notched, forward ends of side members 26 of the lid closing frame 24 strike the tabs 76 on the end wings 71 (Figs. 9, 11 and 12) of the top straightening assemblies 60 and return them to their dependent position shown in Figs. 4 and 10. The biased articulated arrangement of the head 60 as controlled by the coil spring 83 and stop screw 80 allows the head 60 to pivot relatively to the arms 63 to allow the wings 70 and 71 and the prong 77 to swing clear of the box 30 when the loop straightening assemblies 60 are swung into and out of engagement with the box 30.

The operation of the lid tucker 140 is quite obvious from the diagrammatic illustrations of Figs. 5 to 7, inclusive. When the hoist 22 is in its lowermost position illustrated in Fig. 1, the lowermost guide roller 112 on each tucker support plate 144 is cradled in the lower end of its guide slot 111 and the cam actuated roller 153 is in its forwardly swung position as shown in Fig. 5. The tucker actuating rods 161, as shown in Figs. 1, 2 and 5 have been drawn to their lowermost position by the engagement of the stop members 160 on the tucker actuating rods 161, by the hoist top frame 22a. This action of the tucker actuating rods 161, 161 draws the tucker support plates 144 downwardly relatively to the studs 110 on the rear end of the lid closing frame 24 as shown in Fig. 5. As the hoist moves upwardly on an operative stroke of the machine, when the hoist top frame 22a engages the upper stop members 159 on the tucker actuating rods 161, the tucker support plates are elevated thereby, causing the cam engaging roller 153 on the triangular plate 150, which is initially restrained against upward movement by the cam bar 155, to swing the triangular actuating member 150 clockwise from its position in Fig. 5 to that in Fig. 6. This rotative movement of the triangular tucker actuating member 150, by means of the link 151 and lever arm 152, swings the tucker angle member 141 forwardly and upwardly, swinging the rounded nose portion 142 thereof upwardly past the upper rear edge of the box. If the lid of the box being lidded should be displaced rearwardly when it is placed in the machine, for example, as shown in Fig. 5, this upward movement of the rounded nose portion 142 would tuck the lid forwardly into place as shown in the diagrammatic sequence of Figs. 5 to 7. Thereafter, the flat face 141a of the angle member 141 will remain in pressing relation against the upper rear side of the box 30 during the remainder of the upward lidding stroke of the hoist 22. The angle member 141 is restored to its normal, downwardly and rearwardly swung position as shown in Fig. 5 upon return of the hoist to its lowered position. This return swing of the angle member 141 to its normal position is accomplished by the engagement of the roller 153 with the sloping upper face 158 of the cam block 157 as the rollers 112 on the studs 110 reach the lower ends of the slotted openings 111 in the side plates, 25, 25.

During the swinging of the tucker angle member 141 into box engaging position, relative movement between the lid closing frame 24 and the tucker support plates 144 is permitted by the slotted holes 145 in the tucker support plates. The studs 110 on the lid closing frame 24 reach the bottoms of these slotted openings at the same time that the tucker angle member 141 has been swung into pressing relation with the rear of the box 30, after which the rear end of the lid closing frame is carried upwardly by the studs 110 riding on the tucker support plates at the bottoms of the slotted openings 145 therein. The time at which movement of the studs 110 occurs in their slotted openings 145 on the return stroke of the hoist 22 is immaterial. It is obvious, however, that the studs 110 will be returned to their lowermost position in these slotted openings by the time the lower stop members 160 on the

tucker actuating rods 161 (Figs. 1 to 4) have returned to their lowermost position as shown in Fig. 1, so as to swing the tucker angle member 141 downwardly and rearwardly to its position shown in Figs. 1 and 5.

5 While I have illustrated and described a preferred embodiment of the present invention, it will be understood, however, that various changes and modifications may be made in the details thereof without departing from the spirit and scope of the invention as set forth in the appended claims.

10 Having thus described the invention, what I claim and desire to protect by Letters Patent is as follows:

15 1. In a machine for lidding wire bound boxes of the type having a hinged lid, and having box supported fasteners and lid supported fasteners adapted to interengage upon closing the box lid; a box support, lid engaging means opposite said support, means for moving said support and said lid engaging means toward each other to close the lid of a box mounted on said support, a fastener straightener pivotally mounted to swing adjacent a box supported fastener, a prong carried by said straightener and positioned to engage a box supported fastener upon a predetermined movement of said straightener, means for operating said straightener at a predetermined stage 20 of the lid closing movement of the support and the lid engaging means, and means for positively moving the straightener to withdraw the prong from fastener engaging position prior to a final closing of the lid.

25 2. In a machine for lidding wire bound boxes of the type having a hinged lid, and having box supported loops and lid supported loops adapted to interengage upon closing the box lid; a box support, lid engaging means opposite said support, and spaced therefrom to receive an open lidded box therebetween, means for moving said support and said lid engaging means toward each other to close the lid of a box mounted on said support, box front presser means mounted to move into pressing relation with a box on said support, a loop straightener pivotally mounted on said presser means to swing adjacent a box supported loop, a prong carried by said loop straightener and positioned to enter and engage a box supported loop upon a predetermined swinging movement of said loop straightener, means for operating said loop straightener in timed relation with the movement of the support and the lid engaging means to draw the loop into straightened position, and means for positively moving the loop straightener to withdraw the prong from loop engaging position prior to a final closing of the lid.

30 3. In a machine for lidding wire bound boxes of the type having a hinged lid, and having box supported fastener elements and lid supported fastener elements adapted to interengage upon closing the box lid; a box support, lid engaging means opposite said support, and spaced therefrom to receive an open lidded box therebetween, means for moving said support and said lid engaging means toward each other to close the lid of a box mounted on said support, box front presser means mounted to have pressing relation with a box on said support during such movement of the support and lid engaging

35 40 45 50 55 60 65 70 means, a fastener straightener pivotally mounted on said presser means, a prong carried by said straightener and positioned to engage a box supported fastener upon a predetermined swinging movement of said straightener, means for operating said straightener in timed relation with relative movement of the support and the lid engaging means to draw the engaged fastener into straightened condition, said straightener being positioned for retracting movement by the lid engaging means during the final portion of relative lid closing movement between the box support and the lid engaging means to withdraw the prong from fastener engaging position.

75 4. In a machine for lidding wire bound boxes of the type having a hinged lid, and having box supported fastening elements and lid supported fastening elements adapted to interengage upon closing the box lid; a box

support, lid engaging means opposite said support, and spaced therefrom to receive an open lidded box therebetween, means for moving said support and said lid engaging means toward each other to close the lid of a box mounted on said support, box front presser means mounted to move into pressing relation with a box on said support, a fastener straightener pivotally mounted on said presser means to swing adjacent a box supported fastener, said straightener comprising a lever arm and a head portion pivotally mounted thereon, stop means mounted to limit pivotal movement of the head portion on the arm, means mounted to bias the pivotally mounted head portion toward stop engaging position, means on said pivotally mounted head portion positioned to engage a box supported fastening element upon a predetermined swinging movement of said lever arm, and means for operating said straightener in timed relation with relative movement of the support and the lid engaging means to draw the engaged fastener into straightened condition prior to a final closing of the lid.

5. In a lidding mechanism for hinged lid wire bound boxes of the type having a plurality of lid supported loops, and a plurality of bendable box supported fastening elements adapted to enter said loops upon closing the box lid, a box support, a lid closing member mounted opposite said support for pivotal and limited sliding movement relative thereto, said lid closing member being spaced from said box support to receive a box with open lid therebetween; a front presser member movable into pressing engagement with a side of a box on said support, means for advancing the lid closing member and front presser member toward the box to close the open lid of a box on said support, a fastener aligning member mounted for movement on said front presser member on an upper portion thereof, timed actuating means mounted to move said aligning member into straightening engagement with a fastening element of a box being lidded, and means carried by said lid closing member and positioned to withdraw the aligning member from fastener engaging position in advance of final closing of the lid.

6. In a machine for lidding wire bound boxes of the type having a lid hingedly connected thereto, a box support, lid engaging means opposite said support, means for moving said support and said lid engaging means toward each other to close the lid of a box mounted on said support, a lid tucker mounted adjacent the hinged connection of the lid to the box for forward and upward movement, and means for operating said lid tucker at an early stage of the lid closing movement of said support and said lid engaging means to urge the lid forwardly on the box to place under tension the hinged connections of the lid to the box, thereby properly to position rearwardly displaced box lids.

7. In a machine for lidding boxes of the type having a lid hingedly connected to a box by encircling wires, a box support, lid engaging means opposite said support, means for moving said support and said lid engaging means toward each other to close the lid of a box mounted on said support, a lid tucker mounted to be disposed rearwardly of the hinged connection of the lid to a box mounted on said support, said tucker having a nose portion adapted to move forward and upward past said hinged connection on a predetermined movement of the tucker, and means mounted to actuate said tucker at a predetermined stage of the lid closing movement of the support and the lid engaging means to move the tucker nose forward and upward past the hinged connection in the direction of the lid, thereby to move forwardly into position for seating any rearwardly displaced box lid.

8. A machine for lidding a produce box having an initially upstanding lid hinged at the rear top edge of the box and carrying at its free edge a plurality of spaced flexible projections to be interlocked with flexible projections carried by the upper edge of the front wall of the box, said machine comprising a support for the box with

its lid in open position, lid engaging means opposite said support, means for moving said support and said lid engaging means toward each other to swing the hinged lid downwardly toward closed position, a lid tucker mounted rearwardly of the hinged connection of the lid to the box and arranged to be moved forwardly toward the box and into contact with the rear edge of the lid, a plurality of support members pivotally mounted adjacent the front wall of the box and adapted to be swung upwardly toward the box in close proximity thereto, means on said support members arranged to engage and straighten the flexible projections on the front wall of the box as the support members are swung upwardly, stop means for arresting the upward swinging movement of said support members, said support members having abutment surfaces disposed in said arrested position in substantially vertical position above the upper edge of the front wall of the box, and means for actuating said tucker as said lid swings toward closed position to contact the rear edge of the lid and urge the lid forwardly to a position wherein the free edge of the lid is disposed to pass close to said vertical abutment surfaces as it approaches closed position, said abutment surfaces being effective to prevent overflowing of the produce as the lid presses the produce into the box.

25. 9. In a machine for lidding a produce box having an initially upstanding lid hinged to the rear top edge of the box, means for moving the lid to closed position on the box, a support member, means for pivotally mounting the support member for rotation about an axis parallel to and adjacent the front wall of the box at substantially the same height as the upper edge thereof and spaced laterally therefrom, means for moving said support about said axis from a depending position toward said front wall and upwardly in close proximity thereto, and means defining a flat abutment surface on said support member movable into a substantially vertical position extending upwardly above the upper edge of said front wall to form a retainer wall for produce immediately adjacent the path of travel of the lid during final closing movements thereof.

40. 10. In a machine for lidding a produce box having an initially upstanding lid hinged to the rear top edge of the box and carrying at its free edge a plurality of spaced flexible folded projections aligned with flexible folded projections carried by the upper edge of the front wall of the box and arranged to be interlocked therewith, means for pivoting said lid into closed position on said box, a straightener device adapted to be pivotally mounted adjacent the front wall of the box for swinging movement upwardly toward the upper edge of the front wall, means for pivoting said straightener, said straightener being positioned to engage one of the folded projections on the front wall during said upward swinging movement to draw the fold into straightened position, means for arresting said upward pivoting movement after said straightening operation with a portion of said straightener projecting above the upper edge of said front wall, and guide means on said projecting portion adapted to intercept a folded projection on said lid as said lid approaches closed position, said guide means being arranged to direct said lid fold into desired position relative to said front wall fold when said lid is closed.

45. 11. In a machine for lidding a produce box having an initially upstanding lid hinged to the rear top edge of the box and a fastening loop extending from the front wall of the box adjacent the upper edge thereof, means for moving the lid to closed position on the box, a loop straightener assembly, means for pivotally mounting the loop straightener assembly adjacent the front wall of the box near the upper edge thereof in position to be swung upward and toward said front wall in close proximity thereto, a loop-straightening prong carried by said loop straightener assembly and extending therefrom in position to enter the loop as the prong is swung upward, and

means defining a flat abutment surface on said loop straightener assembly movable into a substantially vertical position extending upward above the upper edge of said front wall to form a retainer wall for produce immediately adjacent the path of travel of the lid during final closing movement thereof.

12. In wire bound box lidding apparatus having a support for a box having a wire loop adjacent the upper edge of a wall thereof, loop-straightening mechanism comprising a prong mounted for rotary motion about an axis spaced forward from the upper edge of a wall of a box disposed on the support, means for turning said prong about the axis with the leading end of the prong moving upward in an arcuate path substantially tangent to the front wall to enter a loop carried by the wall, and means defining a shoulder on the prong engageable with the bight portion of the loop to straighten the loop and dispose the same in predetermined position.

13. Loop straightening mechanism for wire bound box lidding apparatus having means for supporting in a predetermined position a box having a wire loop adjacent an upper edge of a wall thereof, said mechanism comprising a support member, a loop straightener assembly mounted on said support member for rotary motion about a predetermined axis, means mounting said support member for movement from an upper, idle position to a lower, operating position wherein said axis is spaced forward from the upper edge of the wall of a box disposed on the support, means operable while said support member is in said lower position for turning the straightener assembly about said axis in a path substantially tangent to the box wall, and means on said straightener assembly engageable with a loop carried by the wall to straighten the loop.

14. Loop straightening mechanism for wire bound box lidding apparatus having means for supporting in a predetermined position a box having a wire loop adjacent an upper edge of a wall thereof, said mechanism comprising a support member, a loop straightener assembly mounted on said support member for rotary motion about a predetermined axis, means mounting said support member for movement from an upper, idle position to a lower, operating position wherein said axis is spaced forward from the upper edge of the wall of a box disposed on the support, means operable while said support member is in said lower position for turning the straightener assembly about said axis in a path substantially tangent to the box wall, a prong mounted on said straightener assembly in position to enter a loop carried by the wall, and means defining a shoulder on said prong engageable with the bight portion of the loop to straighten the loop and dispose the same in predetermined position.

15. Loop straightening mechanism for wire bound box lidding apparatus having an elevator for raising in a predetermined path a box having a wire loop on a wall thereof, said mechanism comprising a support member, a loop straightener assembly mounted on the support member for rotary motion about a predetermined axis, means mounting said support member for movement from

an idle position to an operating position adjacent the path of a box being raised by the elevator, means operable when the axis is substantially in horizontal alignment with a loop on a wall of the box for turning said straightener assembly about said axis in a path substantially tangent to the box wall, and means on the straightener assembly engageable with the loop to straighten the same.

16. Loop-straightening mechanism for wire bound box lidding apparatus having an elevator for raising in a predetermined path a box having a wire loop on a wall thereof, said mechanism comprising a support member, a loop straightener assembly mounted on the support member for rotary motion about a predetermined axis, means mounting said support member for movement from an idle position to an operating position adjacent the path of a box being raised by the elevator, means operable when the axis is substantially in horizontal alignment with a loop on a wall of the box for turning said straightener assembly about said axis in a path substantially tangent to the box wall, a prong on the straightener assembly in position to enter the loop as the straightener assembly is turned, and means on the prong engageable with the bight portion of the loop to straighten the loop and dispose the same in predetermined position.

17. Loop-straightening mechanism for wire bound box lidding apparatus having an elevator for raising a box having a wire loop on a wall thereof, said mechanism comprising a support member, a loop straightener assembly mounted for pivotal movement on the support member, means movable with the elevator pivotally mounting the support member for rotary motion from an idle to an operating position to dispose said straightener assembly adjacent the path of a box being raised by the elevator, means operable during an early stage of upward movement of the elevator for rotating the support member to said operating position, said turning means becoming inoperative upon arrival of the support member in said operating position and the support member being movable in translatory motion with the elevator during a later stage of upward movement thereof, means for pivoting said straightener assembly on the support member toward the box and upward with respect to the same, a stationary cam mounted adjacent the path of the elevator in position to engage and actuate said pivoting means during said translatory motion of the support member, and means on said straightener assembly engageable with the wire loop to straighten the same upon upward swing of the straightener assembly.
